[57] CLAIM

The ornamental design for a hinge wing cover, as shown and described.

DESCRIPTION

FIG. 1 is a perspective view of a hinge wing cover showing my new design, a typical hinge being shown in broken lines to illustrate the relation of the cover to the hinge;

FIG. 2 is an enlarged rear view of the hinge wing cover;

FIG. 3 is a left side elevational view thereof;

FIG. 4 is a front view thereof; and,

FIG. 5 is a right side elevational view thereof.

The broken line showing of the hinge is for illustrative purposes only and forms no part of the claimed design.
